[57] CLAIM

The ornamental design for a three way Y-shaped respiratory valve, as shown and described.

DESCRIPTION

FIG. 1 is a perspective view of a three way Y-shaped respiratory valve, showing our new design;

FIG. 2 is a side elevational view thereof;

FIG. 3 is a front elevational view thereof;

FIG. 4 is a side elevational view thereof, opposite that shown in FIG. 2;

FIG. 5 is a rear elevational view thereof;

FIG. 6 is a top plan view thereof; and

FIG. 7 is a bottom plan view thereof.

Fig.1.**Fig. 2.****Fig. 3.****Fig. 4.****Fig.5.**

Fig.6.
